EXPANDER FOR METAL CONTAINER COVERS

John F. Johnson, Richmond, Calif., assignor to Standard Oil Company of California, San Francisco, Calif., a corporation of Delaware

Application April 7, 1931. Serial No. 528,307

7 Claims. (Cl. 113—19)

My invention relates to rotary expanding devices for securing metal covers to metal receptacles and has particular reference to a device for securing insertable metal covers to seal holes in metal containers.

Metal receptacles for containing liquids or solids which must be sealed, frequently comprise a metal can or barrel, one head of which is provided with an opening through which materials to be placed in the receptacle may be inserted. The opening is thereafter to be sealed by the insertion of a circular metal cover or seal which must be expanded into sealing relation with the edges of the opening. It is, therefore, an object of my invention to provide a tool which may be readily employed to expand a seal and to crimp the edges of such seal around the edges of the opening in a receptacle.

It is, therefore, an object of the invention to provide a tool for expanding insertable seals in containers in which the effective expansion of the seal may be regulated and adjusted to insure proper sealing of the cover with the container.

Another object of the invention is to provide a tool for crimping circular seals placed in circular openings in a container in which a plurality of rollers are provided for engaging and crimping edges of such seal and in which the distance between the rollers may be adjusted to insure sufficient expansion of the seal to form a completely tight seal with the container.

Another object of the invention is to provide a tool of the character described in the preceding paragraph in which the rollers are so mounted that rotary motion of the tool in the sealing operation causes expansion of the rollers to insure tight sealing engagement of the seal and container.

My invention will be described with reference to the accompanying drawing, wherein

Figure 1 is a top elevational view of an expander constructed in accordance with my invention;

Figure 2 is a side elevational view of the expander shown in Fig. 1;

Figure 3 is a detail sectional view of one of the crimping rollers employed with the expander shown in Fig. 1;

Figure 4 is a detail sectional view taken along line IV—IV of Fig. 1, illustrating the manner of adjusting the relative positions of the rollers when the expander is in operation;

Figure 5 is a detail sectional view of a receptacle fitted with a cover to be sealed with the expander shown in Fig. 1; and

Figure 6 is a detail sectional view similar to Fig. 5, illustrating the seal after it has been sealed and crimped by my expander.

Referring, particularly, to Fig. 5 of the drawing, I have illustrated therein a container 1 which is illustrated as being formed of metal having a metal drum head 2 secured as a closer for one end of the container. The head 2 has formed therein a filler opening 3, as by means of punching a circular hole in the head 2 and striking the edges of the surrounding material downwardly to form an inwardly projecting peripheral flange 4.

A seal or closer for the opening is illustrated at 5 as comprising a substantially cup-like circular member constructed of such external diameter as to just fit the peripheral flange of the opening 3. Preferably the outer edges of the seal or closer 5 are turned outwardly to form a radially extending flange 6 which is arranged to abut the outer surface of the drum head 2 when the closer is placed within the opening.

The mere insertion of the closer 5, however, is not sufficient to seal the same in place, and it is necessary to expand the upstanding walls 7 of the closer 5 into sealing engagement with the edges of the opening and to the flanges 4 surrounding the same. For this purpose, I have provided an expanding tool illustrated particularly in Figs. 1 and 2 which comprises a pair of plates 8 and 9. These plates are illustrated as being substantially triangular in formation and may be formed either as a single flat plate or as a plurality of relatively square strips of material forming a triangle. But one plate may be used for the frame, if desired.

The two plates 8 and 9 are illustrated as being mounted one upon the other and spaced from each other as by means of spacers 10 inserted therebetween. The spacers are illustrated as surrounding shafts 11 and 11a, one of which is provided at each of two apices of the triangle formed by the plates 8 and 9. To the lower end of each of the shafts 11 and 11a is secured, respectively, a crimping roller 12 and 12a, these rollers being rotatably mounted upon the associated shaft. Handles 26 and 26a are mounted upon the upper ends of shafts 11 and 11a.

By referring, particularly, to Fig. 3, it will be observed that each of the rollers 12 and 12a is formed with a cross section including an outwardly extending radial flange 13, a radial recess 14 and a curved outwardly extending flange 15, so that when the roller 12 is forced into engagement with the seal 5, the flange 15 will expand

the lower side of the seal 5 into sealing engagement with the depending flange 4 and will bend the flange 4 backwardly upon itself, as is indicated in Fig. 6.

5 At the third apex of the triangle formed by the plates 8 and 9, I have illustrated a pivot pin 16 which extends through both plates and is secured thereto. The pivot pin 16 constitutes a pivot upon which a handle lever 17 may be 10 mounted.

The handle 17 is illustrated as comprising an elongated bar upon each end of which is mounted a handle 18 and the bar is provided intermediate its ends with an outwardly projecting lug 19 which constitutes the mounting for a third roller 20. The roller 20 is illustrated as being mounted upon a stub shaft 21 secured as by means of a nut 22 to the handle bar 17.

By referring, particularly, to Fig. 5, it will be 20 observed that when the device is assembled all three rollers 12, 12a and 20, will lie in the same horizontal plane so that all three of the rollers may be inserted within the cup-like seal or closer 5.

25 It will be observed, also, that the pivotal connection 16 of the handle bar 17 and the mounting of the roller 20 is such that the material between the pivot 16 and the shaft 21 constitutes one arm of a lever which permits the roller 20 30 to be drawn inwardly toward rollers 12 and 12a when the handle bar 17 is rotated in a counter-clockwise direction about the pivot 16 with regard to plates 8, 9, while when the handle bar is moved in a clockwise direction, the roller 20 will 35 be moved outwardly with respect to the rollers 12 and 12a.

40 It will be observed that the left-hand end of the handle bar 17 will move laterally between the shafts 11 and 11a as the handle bar 17 is rotated either clockwise or counter-clockwise. Hence by providing a plurality of aligned openings 23 in the leg 24 of each of the plates 8 and 45 9, which leg lies between the shafts 11 and 11a, and by inserting a cotter pin 25, or other suitable 50 obstruction, through such openings, the relative outward movement of the roller 20 with respect to rollers 12 and 12a may be adjustably limited to conform with the particular size cover or closer 5 with which the tool is to be used and the amount it is to be expanded.

The operation of my device is as follows: When 55 the closer 5 has been inserted in the drum head 2, the handle bar 17 of the expanding tool may be rotated in a counter-clockwise direction to contract the rollers 12, 12a and 20, permitting the insertion of all three rollers within the side walls 7 of the closer 5. Then the handle bar 17 may be 60 rotated in a clockwise direction while handles 26 and 26a are held stationary to first cause the roller 20 to move outwardly relative to the rollers 12 and 12a. This will cause all three rollers to engage the side wall 7 of the closer or seal 5 and will force the side wall into intimate contact 65 with the depending flanges 4 upon the drum head 2. The handles 26 and 26a are then released and all the turning force exerted upon the handle bar 17. Hence, as the clockwise rotation of the tool is continued, the metal of the seal 5 will be 70 pressed further outwardly to bend backwardly the depending flange 4 and to seat the metal of the closer 5 well under the edges of the openings 3. A rotation of 360° is not essential as a partial 75 rotation of the tool after insertion and expansion will be sufficient to insure that the rollers 12, 12a

and 20 will engage and press all portions of the closer 5.

To insure that the expansion of the closer 5 will not be beyond the desired limits, that is, not sufficient to break the metal of which the seal is formed, the cotter pin 25 may be inserted in the proper one of the group of holes 23 so that the outward movement of the roller 20 is limited to only such distance as will be required to make a proper seal. 80

While I have illustrated and described the preferred embodiment of my invention, I do not desire to be limited to any of the details shown or described herein, except as defined in the 85 appended claims.

I claim:

1. A tool for expanding circular metal closers into sealing engagement with containers, a plurality of crimping rollers, means mounting all 90 of said rollers in the same horizontal plane said mounting means comprising two relatively movable members pivoted to move in a plane parallel to the plane of said rollers, certain of said rollers mounted upon one of said members and the remaining rollers mounted upon the other of said members in offset relation relative to said pivot whereby relative movement of said mounting members will move its rollers toward or away 95 from the remaining rollers. 100

2. A tool for expanding circular metal closers into sealing engagement with containers, a plate, a plurality of crimping rollers carried by said plate and lying in the same horizontal plane, a handle member, pivot means spaced from said 105 rollers securing said handle member to said plate for pivotal movement relative to said plate in a plane parallel to the plane of said rollers, an additional roller mounted upon said handle member and lying in the same plane as said other rollers, said mounting of said additional roller 110 being spaced from said pivot pin. 115

3. A tool for expanding circular metal closers into sealing engagement with containers, a pair of plates secured to and spaced from each other, a plurality of crimping rollers mounted upon said 120 plates in spaced relation to each other and lying in the same horizontal plane, a handle member, a pivot means secured to said plates in spaced relation to said crimping rollers and pivotally securing said handle member to said plates for movement 125 in a plane parallel to the plane of said crimping rollers, and an additional crimping roller mounted upon said handle member in spaced relation to said pivot pin and lying in the same horizontal plane as said other crimping rollers. 130

4. A tool for expanding circular metal closers into sealing engagement with containers, a pair of plates secured to and spaced from each other, a plurality of crimping rollers mounted upon said 135 plates in spaced relation to each other and lying in the same horizontal plane, a handle member, a pivot means secured to said plates in spaced relation to said crimping rollers and pivotally securing said handle member to said plates for movement in a plane parallel to the plane of said crimping rollers, an additional crimping roller mounted upon said handle member in spaced relation to said pivot pin and lying in the same horizontal plane as said other crimping rollers, and means adjustably limiting the relative movement 140 of said handle member and said plates. 145

5. A tool for expanding circular metal closers into sealing engagement with containers, a pair of plates secured to and spaced from each other, a plurality of crimping rollers mounted upon said 150

plates in spaced relation to each other and lying in the same horizontal plane, a pivot pin secured to said plates in spaced relation to said rollers, a handle member pivotally secured to said pivot pin and extending beyond said plates in two directions for movement relative to said plates in a plane parallel to the plane of said rollers, an additional crimping roller secured to said handle member in spaced relation to said pivot pin and lying in the same plane as said other rollers, and means insertable through said plates for engaging said handle member and limiting the movement of said handle member relative to said plates.

6. A tool for expanding circular metal closers into sealing engagement with containers, comprising a plate of relatively triangular configuration having crimping rollers at two of its apices, said rollers lying in the same horizontal plane and having at the third apex a pivot pin extending at right angles to the plane of said rollers, a handle member pivoted to said pivot pin, a third roller

secured to said handle member and lying in the same plane as said other rollers, the axis of said third roller being spaced from the said pivot pin.

7. A tool for expanding circular metal closers into sealing engagement with containers, a plate, a plurality of crimping rollers carried by said plate and lying in the same horizontal plane, a handle member, pivot means spaced from said rollers securing said handle member to said plate for pivotal movement relative to said plate in a plane parallel to the plane of said rollers, an additional roller mounted upon said handle member and lying in the same plane as said other rollers, said mounting of said additional roller being spaced from said pivot pin and each of said crimping rollers comprising a radial flange for engaging the top of said closer member, and a second radial flange spaced from said first flange for engaging the side wall of said closer below said top.
